PLATE OR SIMILAR ARTICLE

Shigeru Masuda, 2486 8th St., Apt. E,
Fort Lee, N.J. 07024

Filed Jan. 17, 1966, Ser. No. 639

Term of patent 7 years

(Cl. D44—15)

The figure is a plan view of a plate or similar article showing my new design, a portion of the design being shown between dotted lines.

The plate is of a conventional configuration when viewed from the side and bottom thereof.

I claim:

The ornamental design for a plate or similar article, substantially as shown and described.
